(57) **CLAIM**

The ornamental design for a grille insert for displaying logo design (dodge design), substantially as shown and described.

DESCRIPTION

FIG. 1 is a front elevational view of the grille insert for displaying logo design (Dodge design) showing my new design.

FIG. 2 is a top plan view thereof.

FIG. 3 is a bottom plan view thereof; and,

FIG. 4 is an end elevational view taken from the left of FIG. 2, the opposite end being the same.

1 Claim, 2 Drawing Sheets
